SPRING SUPPORTED CHILD'S CRIB

Elmer F. Borrelli, Philadelphia, Pa.

Application April 1, 1946, Serial No. 658,792

8 Claims. (Cl. 5—104)

1

This invention relates to crib beds, and more particularly to improvements in sleeping cribs adapted for use by young infants and small children.

The ordinary sleeping crib, when in actual use, remains stationary at all times. When a child occupying the crib awakens and becomes restless, it usually cries. In most instances, the crying child is lifted by a parent or nurse from the stationary crib and is rocked or walked until sleep returns, whereupon the sleeping child is again placed in the crib.

The primary object of the present invention is to provide a delicately balanced spring supported crib which will react to the slightest motion of the child, whereby, when the child awakens and becomes restless, and as a consequence of such restlessness tosses and rolls or otherwise moves about in the crib, the crib will automatically receive a universal rocking or swaying motion, with the result that the child will be effectively rocked back to sleep without the need of a parent or nurse entering the nursery, picking up the child and rocking or walking it, or in any way moving the crib by manual operation.

Another object of the present invention is to construct the crib in such a manner that it may be poised and balanced at a predetermined angle to the horizontal, whereby, upon the slightest motion of the occupant, there will result a rocking motion of the crib, both laterally and longitudinally, which will tend to put a waking child back to sleep.

Another object of the present invention is to provide a crib which may be adjusted to and rigidly maintained in any one of a number of angular positions as may be required for a particular child, to remain in such positions as long as desired.

The invention includes other features and advantages which will become apparent from the following description of a typical embodiment of the invention as illustrated in the accompanying drawings, of which:

Fig. 1 is a side elevation of the device;

Fig. 2 is an end elevation, partly in section;

Fig. 3 is an enlarged sectional plan view of the device taken on the line 3—3, Fig. 2;

Fig. 4 is a sectional view taken on the line 4—4, 50 Fig. 2; and

Fig. 5 is a sectional view taken on line 5—5 of Fig. 1.

The crib primarily comprises a bed structure A, a base structure B, and a spring supporting

2

structure C interposed between said base and said bed structures.

The bed structure A comprises a pair of transversely extending end panels 1 and 2, a pair of longitudinal side panels 3 and 4, and a bottom member 5. Attached to the under surface of the bottom member 5 of the body A are two parallel longitudinal beam elements 6 and 7.

Secured to the opposite ends respectively of the longitudinal beam elements 6 and 7, are shackle brackets or hangers 8, 8, respectively. The brackets 8, 8 are forked at their outer ends to receive the ends of shackle links 9, 9 therebetween. Shackle bolts 10, 10 extend transversely of said forked brackets 8, 8 and serve as fulcrums for one end of shackle links 9, 9 which are pivoted thereto. The opposite ends of the shackle links 9, 9 are pivoted about a similar series of shackle bolts 11, 11 which extend transversely through brackets 12, 12 secured to the opposite ends of a pair of longitudinal spring members 13 and 14, running parallel with and lying beneath the beam members 6 and 7 respectively.

At the respective center points of the spring members 13 and 14, said longitudinal springs are secured to the opposite ends of a transversely extending cross bar 15, said cross bar being attached to said spring members 13 and 14 by screws 16, 16. Beneath the cross bar 15, and attached thereto as by screws 17, 17 is one arm 18 of a Z-shaped transverse spring member 20, the bottom arm 19 of which is attached to a shaft 25, as by screw members 24, 24.

The shaft 25 is rotatably mounted in a pair of split bearings 26 and 27 respectively carried by side stringers 28 and 29 of the base or frame structure B.

The base structure B comprises said longitudinally running base members 28 and 29, transversely extending end members 30 and 31, and upright corner post members 33, 33 and within the area established thereby the said crib structure A is adapted to rock.

At one end of the shaft 25 there is formed an enlarged drum 40 which is adapted to rotate within the split bearing 26. The relatively movable parts of the split bearing 26 are adapted to be drawn snugly around the drum 40 by bolts 41 and 42, to frictionally hold the drum 40 and the crib structure A in any one of a number of angular tilted positions relative to the base structure B, with the crib structure A free to rock longitudinally and transversely at will.

On the end of the shaft 25, adjacent the drum 40, is a disc 46 having a plurality of holes or in-

dentations 47, 47 which are adapted to receive a spring detent 50. The detent 50 is secured to the longitudinal rail 28 of the base structure B and is adapted to hold the shaft 25 and the crib structure A in its aforesaid tilted positions coordinate with the friction drum 40. A foot release pedal 55 (see Fig. 5) is adapted to release the detent 50 from the disc 46 when the crib structure A is being tilted manually.

In operation, the crib structure A is adapted to rock both forwardly and backwardly and sideways as a result of the resiliency of the longitudinal spring members 13 and 14 and the transverse spring member 20. Due to universal resiliency teetering action afforded by the spring supporting mechanism C, the body A of the crib will react to any motion of a sleeping or waking occupant, with the resulting effect that a child on awakening, will tend to be rocked to sleep again, due to such motion. The slightest motion of the child will have a corresponding effect on the crib.

If it is desired to maintain the crib in a stationary position, locking pins 60, 60 are adapted to be inserted selectively in particular holes of the series of holes 61, 61 formed in the upright corner posts of the base structure B, and in a series of holes 62, 62 formed in the corner posts of the crib structure A, so that the desired position may be obtained and maintained.

I claim:

1. A crib comprising a stationary base structure, a relatively movable body structure, and an intermediate spring supporting structure connecting said body structure to said base structure and including a transverse spring carried by said base structure, a pair of laterally spaced longitudinal springs carried by said body structure and centrally connected to said transverse spring, a transverse shaft rotatably mounted in said base structure and supporting said transverse spring therein, and means for frictionally maintaining said shaft in any one of a number of adjusted positions circumferentially of said shaft.

2. A crib comprising a stationary base structure, a relatively movable body structure, and an intermediate spring supporting structure connecting said body structure to said base structure and including a transverse spring carried by said base structure, a pair of laterally spaced longitudinal springs carried by said body structure and centrally connected to said transverse spring, a shaft rotatably mounted in and extending transversely of said base structure, means securing said transverse spring to said transverse shaft, an indented disc secured to said shaft, and a spring detent carried by said base structure and engageable with the indentations in said disc for maintaining said body structure selectively in any one of a number of longitudinally tilted free rocking positions relative to said base structure.

3. A crib comprising a stationary base structure, a relatively movable body structure, and an intermediate spring supporting structure connecting said body structure to said base structure and including a transverse spring carried by said base structure, a pair of laterally spaced longitudinal springs carried by said body structure and centrally connected to said transverse spring, a shaft rotatably mounted in and extending transversely of said base structure, means securing said transverse spring to said transverse shaft, an indented disc secured to said shaft, a spring detent carried by said base structure and engage-

able with the indentations in said disc for maintaining said body structure selectively in any one of a number of longitudinally tilted free rocking positions relative to said base structure, and foot release means for disconnecting said detent from said disc.

4. A crib comprising a stationary base structure, a relatively movable body structure, a pair of spaced parallel spring members supporting said body structure and to which the body structure is attached, a cross bar extending between said spring members and connected thereto substantially midway between the ends of the spring members, and another spring member interposed between said base structure and said cross bar, and secured both to the base structure and the cross bar, and serving as the sole means for supporting the body structure and the first-mentioned spring members on the base structure.

5. A crib comprising a stationary base structure, a relatively movable body structure, a pair of spaced parallel spring members supporting said body structure and to which the body structure is attached, and a Z-shaped spring member extending transversely with respect to said first-mentioned spring members and interconnecting the latter with said base structure, and serving as the sole means for supporting the body structure and the first-mentioned spring members on the base structure.

6. A crib comprising a stationary base structure, a relatively movable body structure, a pair of spaced parallel spring members supporting said body structure and to which the body structure is attached, a cross bar extending between said spring members and connected thereto substantially midway between the ends of the spring members, and a Z-shaped transverse spring member interposed between said base structure and said cross bar, and secured both to the base structure and the cross bar, and serving as the sole means for supporting the body structure and the first-mentioned spring members on the base structure.

7. A crib comprising a stationary base structure, a relatively movable body structure, and an intermediate spring supporting structure connecting said body structure to said base structure and including a transverse spring carried by said base structure, a pair of laterally spaced longitudinal springs carried by said body structure and centrally connected to said transverse spring, a transverse shaft rotatably mounted in said base structure and supporting said transverse spring therein, whereby said body structure may be disposed in any one of a number of longitudinally tilted free rocking positions relative to the base structure, and means cooperatively associated with said shaft for maintaining said body structure in any one of said positions.

8. A crib comprising a stationary base structure, a relatively movable body structure, and an intermediate spring supporting structure connecting said body structure to said base structure and including a transverse Z-shaped spring carried by said base structure, a pair of laterally spaced longitudinal springs carried by said body structure and centrally connected to said transverse spring, a transverse shaft rotatably mounted in said base structure and supporting said transverse spring, the lower arm of the transverse Z-shaped spring extending along and being secured to said shaft, said body structure being disposable in any one of a number of longitudinally tilted free rocking positions relative to the base structure.

by virtue of the rotatability of said shaft, and means cooperatively associated with said shaft for maintaining said body structure in any one of said positions.

ELMER F. BORRELLI.
